LIGHT CONDUCTIVE PANE OR THE LIKE

Morris M. Buzan, Jennings, Mo., assignor to Day-Brite
Lighting, Inc., St. Louis, Mo., a corporation of Missouri

Application April 3, 1957, Serial No. 45,575

Term of patent 14 years

(Cl. D36—11)

FIG.1

FIG.2

FIG.3

FIG.4

Fig. 1 is a perspective view of a fragmentary portion of a light conductive pane or the like, showing my new design;

Fig. 2 is a top plan view;

Fig. 3 is a cross-sectional view on line 3—3 of Fig. 2; and

Fig. 4 is a cross-sectional view on line 4—4 of Fig. 2.

I claim:

The ornamental design for a light conductive pane or the like, as shown.
